MACHINE FOR MAKING MANIFOLD FORMS

George L. Fulk, San Francisco, Calif., assignor
to Carbon Interleaved Forms Corporation, Nor-
walk, Ohio, a corporation of Ohio

Application November 14, 1936, Serial No. 110,876

10 Claims. (Cl. 270—52)

This invention relates to a method and apparatus for making manifold forms, in which one-time carbons are employed for making a record, and in which the carbons may be quickly removed from their position in the pack at the completion of the record.

The present invention is an improvement over that shown by my copending application, Serial No. 63,282, filed February 10th, 1936. Manifold 10 packs of the type with which this invention is concerned usually have three or more record sheets interleaved with the transfer strips to form a single unit, and frequently a large number of units are fastened together in superimposed relationship to form a pack.

An object of the present invention is to provide a method and apparatus for making a manifold pack, which will insure registration of the interleaved strips so as to maintain uniformity of the various units and to maintain accurate 20 registration of the printed webs.

Other objects of the invention will become more apparent from the following description, reference being had to the accompanying drawings, in which I illustrate a preferred embodiment of the invention. The essential features of the invention will be set forth in the claims.

Referring now to the drawings, Fig. 1 is a side elevation of a machine embodying my invention; Fig. 2 is a top plan view of the machine; Fig. 3 is a side elevation partially in section of a portion of the machine, but shown on a much larger scale than Fig. 1; Fig. 4 is a section taken on the lines 4—4 of Fig. 3; Fig. 5 is a diagram illustrating the relationship of certain rolls of the web-feeding mechanism to the web; Fig. 6 is a view illustrating the manner in which the superimposed record and transfer strips are assembled; Fig. 7 is a view of the unit after it has 40 been separated from the assembled strips.

The manifold pack with which the present invention is particularly concerned may include any number of record strips, such as, for example, those indicated in Fig. 6, at 10, 11, 12, and 45 13, interposed with suitable transfer strips 14, 15 and 16. The record and transfer strips are fastened together, preferably with an adhesive along one edge above the perforation line 17, while the lower edges 18 of the transfer strip 50 terminate above the bottom edges of the record strip. This arrangement enables the operator to grasp the portion 20 above the perforated line, with the thumb and forefinger of one hand, and the overhanging portion beneath the lowermost 55 edges of the transfer sheet with the thumb and

forefinger of the other hand. The two portions are then snapped apart, thus leaving the detached record strips of the unit in one hand and the detached transfer strips of the unit in the other hand. The transfer strips are then discarded and the record strips are filed for future use.

To make the pack 21 illustrated in Fig. 7, I take rolls 30 of webs W with the desired forms printed thereon, and I provide each web with a 10 series of openings 22 along one longitudinal edge thereof. I utilize these openings for receiving projections on feeding rolls to hold the strips in registration during assembling operation. The record strip rolls are indicated in Figs. 1 and 3 15 at 30 and are freely movable on a support, such as a bar 31. These bars are shown as extending laterally from a frame 32, and correspond in number to the number of record sheets required to form the desired pack.

The webs or strips W are fed from their respective rolls 30 upwardly by a pair of feeding rollers 33 and 34, hereinafter to be more fully described. From their respective feed rollers each web passes upwardly around respective 25 guide bars 37 and 38, after which it passes over a drum 40. Each drum is drivingly secured to a shaft 42 journalled in the frame 32, and carries a series of radially extending pins 41 which project into the web openings 22 to align 30 the longitudinal edges of each web, as well as to align the printed form on one web with the printed forms on the other web.

Suitable rolls 45 provided with recesses for receiving the pins 41 of the drums 40 are positioned above the respective drums, and coact therewith to retain the webs in position. Each roll 45 is journalled at the free end of an arm 47, which is pivotally mounted on the frame as at 48 and preferably arranged to permit adjustment of the position relative to its respective drum 40.

The transfer strip is inserted between the record strips and to this end I have shown transfer strips 50 in roll form, journalled on suitable 45 shafts 51, carried by the frame 32. The web from each transfer roll extends downwardly, forming a loop 52 within which a weight 53 is cradled, thence upwardly over the guide bar 54, thence around the guides 38 of the associated 50 record strip where it passes between adjacent webs of record strips and over the respective drums 40.

The transfer strips and record strips are connected together preferably by an adhesive mate- 55

rial. This adhesive may be applied by paste rollers 60 which are journaled within paste containers 61, carried by the frame 32. Each paste roller has two contacting surfaces, one of which 5 forms the adhesive line 58 (Fig. 6) by means of which adjacent record strips are fastened together, the other of which forms a line 59 (Fig. 6) by means of which the back of each transfer strip is fastened to the back of the superimposed 10 record strip. The upper edge of the record strip terminates between the adhesive lines 58 and 59, while the adhesive line 58 is below the line of perforation 22.

After the record strips and the interposed 15 transfer strips have been completely assembled and secured together as above described, the portions of the record strip carrying the aligned openings 22 which are utilized for maintaining the webs in accurate alignment and registration 20 are removed by a shearing operation. This shearing operation may be performed, as indicated by a rotary cutter 10 driven by the motor 35 as shown in Fig. 2. After the portion of the record strip carrying the aligned openings 22 has been cut off, 25 as just described, the assembled web, composed of record strips, and interposed transfer strips, is cut to form individual packs each of which comprises a plurality of secured sheets. These packs are from the assembled web by a cutter (not 30 shown), which is adapted to be reciprocated vertically within the guide 71 by an eccentric 72 which is rigid with a shaft 73. This eccentric is connected by a rod 74 to the carrier, on which the cutter is mounted. The cutter is positioned adjacent 35 the table 78 on each side of which an eccentrically operated rod 74 is disposed and beneath which the shaft 73 is journaled. The shaft, in turn, is operated in timed relationship to the assembling mechanism by suitable gearing from 40 the motor 35. If desired, however, a rotary shearing mechanism may be used, such as shown and illustrated in my copending application, Serial No. 99,104, filed Sept. 2, 1936.

The present invention is particularly concerned 45 with a web feeding mechanism interposed between the drum 40, and each roll of paper 30. This feeding mechanism is arranged to feed the webs from the rolls 30 to the respective drums 40, in such a manner as to cause the openings 22 to 50 align with, or fall on the pins 41. This prevents the tearing of the paper web and at the same time facilitates the starting up of the press, by enabling the press to be brought up to its normal or maximum speed with rapidity, without danger 55 of breaking the web. This mechanism includes the feeding rolls 33 and 34, heretofore mentioned.

As shown in Figs. 3 and 5, each web W passes 60 upwardly from its respective roll 30, over and around its feed roll 34, thence downwardly around its feed roll 33, thence upwardly around guide rolls 37 and 38, to its respective drum 40. It will be noted that the rolls 33 and 34 are spaced apart and do not actually grip the paper between them. However, the arrangement is such that these 65 rolls frictionally engage the paper over a large portion of their periphery. These rolls are positively driven and their peripheral speed is slightly in excess of the peripheral speed of the drum 40. Due to their frictional engagement with the paper 70 the rolls 33 and 34 will draw the paper from the roll 30 and lead it upwardly at a rate of speed slightly faster than the peripheral speed of the roll 40, thereby causing the openings 22 of the paper to fall on the pins 41 of their respective 75 drums 40.

By driving the rolls 33 and 34, the feeding action of the pins 41 is limited to that required to take up the web slack between the drum and the feed roll 33, and maintain the frictional contact of the web with the rolls 33 and 34, such frictional contact being sufficiently great to withdraw the paper from the roll 30. In addition the friction between these rolls is sufficient to enable the machine to be started up at a comparatively high rate of speed, initiating the movement of the rolls 10 30 and withdrawing the webs W, without placing any strain on the line of perforations, thereby insuring exact registration of the web.

As heretofore mentioned, the drum 40 normally maintains the web in frictional contact with the 15 feed rolls. As the feed rolls are positively driven at a rate of peripheral speed which is greater than the peripheral speed of the drum 40, they tend to slacken the web between the drum and such rolls. There is, however, a drag on each 20 roll 30 of web material, in the form of a weight 55 which is supported by an arm 56 pivoted to the frame 32 at 57 and which is positioned to ride on the periphery of its respective roll 30. Due to this drag any tendency of the feed rolls to slacken 25 or relieve the tension on the web decreases the contact pressure between the feed rolls and the web, thereby permitting the surface of the rolls to slip relative to the web and retard the feeding 30 of the web. This slippage prevents the accumulation of web slack between the feed rolls and the drum 40.

The rolls 33 and 34 are driven by the motor 35 which also drives the drums 40. As shown in the drawings, especially in Figs. 1 and 3, the motor 35 is connected by a driving chain or belt 80, with a line shaft 81, to which is secured a series of worm gears 82, which mesh with respective worm wheels 83, secured to the shafts 42 of respective rolls 40. Also drivingly secured to each roll shaft 40 42 is a gear 84, which through the medium of idler gears 85 drive respective pinions 86, carried by the rolls 34. Secured to each roll 34 is a pinion 87, which meshes with a corresponding pinion 88, on the coacting roll 33, thus driving 45 both rolls in synchronism with each other and slightly in excess of the peripheral speed of the roll 40.

The driving relationship between the rolls 34 and 33 and the diameters of such rolls are such 50 that the peripheral speed of the rolls 33 and 34 is slightly in excess of the peripheral speed of the drums 40. This ratio of the peripheral speeds, by way of illustration, is thirty four and one sixteenth inches per minute to thirty four inches 55 per minute.

From the foregoing description it will be apparent that I have provided an apparatus, by means of which multiple sheet forms may be expediently assembled by using webs of form material 60 with webs of transfer material, securing the various webs together, assembling the webs of the pack without interrupting the progress of the material at any stage of the operation, and I have so arranged the web feeding mechanism as 65 to insure utmost accuracy in the registration of the record sheets, as well as to maintain accurate width of the pack and the various records of the individual packs.

I claim:

1. The method of making a manifold pack in which transfer strips are interleaved between record strips, comprising continuously withdrawing elongated webs of record and transfer materials from respective rolls at predetermined rates 75

- of speed, bringing such webs of material together in interleaved relationship at a predetermined rate of speed, slightly less than the rate of speed of withdrawal of the webs from the roll, securing 5 the webs together while moving at the last named predetermined speed, subsequently shearing the webs into individual packs without interrupting the movement of the web.
2. The method of making a manifold pack in 10 which transfer strips are interleaved between record strips, from rolls of perforated record strip material and rolls of transfer strip material comprising withdrawing the transfer material from the rolls, continuously withdrawing elongated 15 webs of record materials from the rolls at a predetermined rate of speed, bringing such webs of material together in interleaved relationship by progressively engaging the perforations at a predetermined rate of speed slightly less than the 20 rate of speed of withdrawal of the webs from the roll, securing the webs together and subsequently shearing the webs into individual packs without interrupting the movement of the web.
3. A machine for making manifold forms, including means for supporting a plurality of rolls 25 of record material and a plurality of rolls of transfer materials, means for withdrawing the strips of material from such rolls, including means to withdraw the record material from such 30 rolls at a predetermined rate of speed, means to interleave such strips of material, means to drive said interleaving means at a rate of speed slightly less than the speed of said withdrawing means.
4. A machine for making manifold forms, including means for supporting a plurality of rolls 35 of perforated record material and a plurality of rolls of transfer materials, means for withdrawing the strips of material from such rolls, including means to withdraw the record material from such 40 rolls without engaging the perforations therein and at a predetermined rate of speed, means to interleave such strips of material including means to engage the perforations, means to drive said interleaving means at a rate of speed slightly less 45 than the speed of said withdrawing means.
5. In a machine for making manifold forms, including means for supporting a plurality of rolls of record and transfer materials, means for assembling said webs including a drum provided 50 with pins adapted to enter the perforations of the webs to maintain registration thereof, means to withdraw the record material from the rolls and feed it to said interleaving means, and means to drive said drum at a peripheral speed which is 55 slightly less than the lineal speed of the web feed.
6. In a machine for making manifold forms, including means for supporting a plurality of rolls of record and transfer materials, means for 60 assembling said webs including a drum provided with pins adapted to enter the perforations of the webs to maintain registration thereof, means to withdraw the record material from the rolls and feed it to said assembling means, said last-named 65 feeding means being arranged and adapted to withdraw the record material from its roll at a rate of speed slightly in excess of the peripheral speed of the interleaving drum.
7. In a machine for making manifold forms, including means for supporting a plurality of 5 rolls of record and transfer materials, means for assembling said webs including a drum provided with pins adapted to enter openings in the webs of record material to maintain registration thereof, means frictionally engaging the web of record material to withdraw the record material from the rolls and feed it to said assembling means, said last named feeding means being arranged and adapted to withdraw the record material from its roll at a rate of speed slightly in excess 10 of the peripheral speed of the interleaving drum.
8. In a machine for making manifold forms, including means for supporting a plurality of 15 rolls of record and transfer materials, means engaging the rolls of record material to retard their rotary movements, means for assembling said webs including a drum provided with pins adapted to enter openings in the webs of record material to maintain registration thereof, means intermediate the drums and the rolls for frictionally engaging the web of record material to withdraw the record material from the rolls and feed it to said assembling means, said last named feeding means being arranged and adapted to withdraw the record material from its roll at a 20 rate of speed slightly in excess of the peripheral speed of the interleaving drum.
9. In a machine for making manifold forms, including means for supporting a plurality of 25 rolls of perforated record material and rolls of transfer material, means for assembling said webs into a pack formation including a drum having pins adapted to engage the perforations, in the webs of record material, means to feed the webs to said drums including a pair of spaced rolls 30 each of which is in frictional engagement with the web over half of its periphery and means to drive the drums and said rolls, said last named means being arranged and adapted to drive the 35 rolls at a rate of peripheral speed in excess of the 40 rate of peripheral speed of the drums.
10. In a machine for making manifold forms, including means for rotatably supporting a plurality of rolls of record material, means to retard the rotary movement of said rolls, means for 45 assembling said webs into a pack formation, said last named means including a drum positioned above the rolls of web material, means to maintain the webs in contact with said drum, means positioned intermediate the rolls and said drum 50 to feed the webs to said drums and including a pair of spaced rollers each of which is normally in frictional engagement with the web over half of its periphery and means to drive the drums and said rollers, said last-named means being 55 arranged and adapted to drive the rollers at a rate of peripheral speed in excess of the rate of peripheral speed of the drums.

GEORGE L. FULK.
